UNITED STATES PATENT OFFICE.

HERBERT M. LOFTON, OF CHATTANOOGA, TENNESSEE.

VALVE.

1,251,792.

Specification of Letters Patent.

Patented Jan. 1, 1918.

Application filed August 21, 1915. Serial No. 46,727.

To all whom it may concern:

Be it known that I, HERBERT M. LOFTON, a citizen of the United States, and resident of Chattanooga, county of Hamilton, and 5 State of Tennessee, have invented an Improvement in Valves, of which the following is a specification.

The object of my invention is to provide a suitable construction adapted to a gate 10 or other valve to indicate when the valve is open and closed, the device being so made that it is capable of adjustment to suit valves requiring a greater or less number of revolutions of the operating stem to open 15 or close the valve.

Heretofore, devices for indicating the open and shut positions of the valve piece have been made to suit the definite number 20 of revolutions required to operate the valve and hence were required to have a special pitch to the screw thread of the operating nut which actuates the targets or indicators to bring them into view at the proper times, and this was undesirable as the indicator 25 mechanism could not be made up in stock and adapted by adjustment to suit any valves, irrespective of the pitch of the valve spindle or stem and the number of revolutions required in opening and closing the 30 valve. By my improvements, the device for operating the targets or indicators is adjustable; hence this attachment for operating the valves and indicating their open and closed conditions may be made up in 35 suitable sizes and then adjusted to suit the different pitch and number of revolutions required to open or close the valve of any make.

My invention consists of certain features 40 of construction fully described hereinafter and more particularly defined in the claims.

Referring to the drawings:—

Figure 1 is a sectional elevation of my improvements applied to a valve; Fig. 2 is 45 a cross section of the same on line α — α ; Figs. 3 and 4 are elevations of the target casting with the targets in position ready for assembling into the apparatus; and Fig. 5 is an elevation of the upper end of the indicator post.

The valve 2 may be of any usual construction, and secured to its upper portion is the lower section 3 of the post. The section 3 of the post is provided at its upper part 55 with a tubular portion over which is adjustably fitted the lower portion of the up-

per section 4 of the post, the two sections being secured together by set screws 5. In this manner the post is adjusted as to its height to suit the depth of the valve in the 60 ground. The post may be made in any other suitable manner if so desired.

Ordinarily, the top of the valve spindle 6 is fitted with a square nut 7 arranged in the lower section of the post. Fitting over 65 this nut 7 is a socket piece 8 formed on the lower end of a stem 9, preferably square in cross section. The square-shaped upper end of the stem fits into a square hole in the operating nut 10 which is journaled in the 70 cap 11 secured upon the top of the head of the upper section, in which it may revolve but held against longitudinal motion. The downwardly extending body of this nut within the head of the post is screw-threaded 75 as at 12. This threaded end of the nut screws through a target casting 13 which is provided with downwardly extending flanges 14 at opposite sides, said flanges parallel and lying in the direction of movement of the casting 13 under the operation 80 of the nut. Each of these flanges is provided with vertical rows of teeth 15, preferably arranged at a distance apart. The flanges are also provided with tapped holes 85 16 at intervals apart and preferably extending through the toothed portions as shown in Fig. 4. This target casting 13 is also provided with a lug 17 at opposite side edges which is guided between lugs 18 on the head 90 of the post so that it is permitted longitudinal motion but held against rotation with the nut 10. Secured upon each of the flanges 14 are two targets 19 and 20, the former containing the word "Shut" and the latter the 95 word "Open." These targets have at their ends slots 21 through which screws 23 extend to engage the tapped holes 16 in the target casting. The backs of the targets are also provided with parallel teeth 22 which 100 engage the teeth 15 on the flanges of the target casting, and when clamped in position by the screws 23 the targets are firmly held to the casting and move with it. By making the slots 21 of a length substantially 105 equal to or greater than the distance between adjacent holes 16, the targets can be adjustably clamped in any positions desired upon the flanges of the target casting.

The head or upper portion of the upper section 4 of the post is provided on oppo-

site sides with openings in which are fitted glass windows 24, said windows held in place by the guards or frames 25 secured to the head by screws. These windows are 5 so positioned that the targets 19 and 20 are brought alternately into position back of the same window, whereby the "shut" or "open" position of the valve may be indicated according to the manipulation of the 10 valve.

By rotating the nut 10 the stem 9 is rotated to open or close the valve. The rotation of the nut simultaneously raises or lowers the target casting 13 to bring the 15 "open" or "shut" targets back of the windows, as the case may be. It is manifest that if the pitch of the thread on the valve stem was different from the pitch of the screw thread on the nut 13, the targets 20 would not move to the same extent; and to compensate for this and insure the targets coming back of the windows at the proper time, it is only necessary to adjust the targets upon the flanges of the target casting, 25 that is, nearer or farther apart as the case may require. This is accomplished by loosening the screws 23 sufficiently to allow the teeth of the targets to be adjusted over the teeth of the flanges, and then again 30 tightening the screws. In this way the positions of the targets may be adjusted to come back of the window to indicate "Shut" when the valve is closed or shut, and to indicate "Open" when the valve is opened, irrespec- 35 tive of the number of turns or revolutions of the valve spindle required to open and close the valve. Either one or two sets of these targets may be employed as preferred.

It will also be understood that this improvement may be utilized with valves 40 which open by turning the nut to the right or to the left as may be required, the only change necessary being to transpose the "open" and "shut" targets. Thus, in a valve 45 that opens to the right, the "open" target will be placed at the top and the "shut" target at the bottom, whereas if the valve turns to the left the "open" target is placed at the bottom and the "shut" target placed at the top.

50 It will thus be seen that with this improvement the construction may be considered as universal for use with any size of valve; any make or type of valve; and for any direction of opening.

55 It will be understood that the nut 10 may screw directly into the target casting 13 or into a bushing therein as shown, and that the general details may be varied in design, as such changes do not act as a departure 60 from the invention.

65 It will now be apparent that I have devised a novel and useful construction which embodies the features of advantage enumerated as desirable, and while I have in the present instance shown and described the

preferred embodiment thereof which has been found in practice to give satisfactory and reliable results, it is to be understood that I do not restrict myself to the details, as the same are susceptible of modification in various particulars without departing from the spirit or scope of the invention. 79

Having now described my invention, what I claim as new and desire to secure by Letters Patent, is:—

1. In a device of the character stated, the valve, rotatable means for opening and closing the valve, a target casting connected to be raised and lowered by the rotatable means, indicating targets secured upon the target casting and relatively adjustable to and from each other, and a casing or head inclosing the targets and target casting having a window or opening through which one or the other of the targets may be seen when the valve is open or closed. 85

2. In a device of the character stated, the valve, rotatable means for opening and closing the valve, a target casting connected to be raised and lowered by the rotatable 90 means said casting having transverse teeth, indicating targets secured upon the target casting and relatively adjustable to and from each other said targets also having transverse teeth engaging the teeth of the 95 casting and vertical slots, screws extending through the slots and engaging the target casting to hold the targets in position, and a casing or head inclosing the targets and target casting having a window or opening 100 through which one or the other of the targets may be seen when the valve is open or closed. 100

3. In a device of the character stated, the valve, rotatable means for opening and closing the valve including a nut having a screw threaded exterior, a target casting connected to be raised and lowered by the screw threaded portion of the nut of the rotatable means, two independent indicating targets 110 secured upon the target casting and relatively adjustable to and from each other, clamping means for holding the targets in adjusted positions upon the casting, and a casing or head inclosing the targets and target casting having a window or opening 115 through which one or the other of the targets may be seen when the valve is open or closed. 115

4. In a device of the character stated, a head adapted for a valve having a window or opening, rotatable means in the head for opening and closing the valve, a target casting guided in the head and movable longitudinally by the rotatable means, and targets carried by the target casting and relatively adjustable to or from each other and arranged to be respectively moved into position back of the windows or opening to indicate when the valve is open and closed. 120 125 130

5. In a device of the character stated, a head adapted for a valve having a window or opening, rotatable means in the head for opening and closing the valve, a target casting guided in the head and movable longitudinally by the rotatable means, and independent targets carried by the target casting and relatively adjustable and reversible upon the casting and to or from each other

and arranged to be respectively moved into 10 position back of the window or opening to indicate when the valve is open and closed.

In testimony of which invention, I hereunto set my hand.

HERBERT M. LOFTON.
